UNITED STATES PATENT OFFICE.

FREDERICK G. JAHN, OF BROOKLYN, NEW YORK, ASSIGNOR TO INTERNATIONAL POSTAL SUPPLY COMPANY OF NEW YORK, OF BROOKLYN, NEW YORK, A CORPORATION OF NEW YORK.

POWER-DRIVE FOR CANCELING-MACHINES.

1,116,070.

Specification of Letters Patent.

Patented Nov. 3, 1914.

Application filed October 23, 1912. Serial No. 727,382.

To all whom it may concern:

Be it known that I, FREDERICK G. JAHN, a citizen of the United States, and resident of Brooklyn, in the county of Kings and State 5 of New York, have invented certain new and useful Improvements in Power-Drives for Canceling-Machines, of which the following is a specification.

This invention relates to canceling machines. The ordinary canceling machine in use, operates upon the plan of feeding letters, checks, cards, or the like, from loose groups or packages held in the right hand, standing vertically on edge, the feeding 10 mechanism snatching the cards or sheets off the group individually with great rapidity, and in a fairly uniform procession or series, although the uniformity is not by any means absolute in the sense that there is an even 15 space between the sheets or cards fed in such procession. These machines are operated by power wherever electricity is available, but obviously since the demands of the machine can not wait for a supply of power 20 during periods that the same is cut off, it is necessary to have a hand operation of the machine. Thus the machines are preferably constructed with both hand operating means and power operating means, and the 25 same must necessarily be quickly changed from one to the other.

In my prior United States Patent No. 856,345 a canceling machine is illustrated having these general standard features of 30 construction, such as a hand wheel on an inclined axis adapted to be spun by the left hand while a package of letters is being held against the feeding wheels by the right hand. This patent also illustrates the general character of the feeding wheel, and the 35 train of gearing by which all the rotating parts are interconnected. It will be observed that a large number of gears are used, and it is practically important that these 40 gears be all immersed in an oil pan, and that the oil pan be without any such openings or bearings extending through its walls as might let the oil escape after such bearings had become worn. Also it will be ob- 45

50 served that the feeding disks are necessarily

located quite close to the surface of the table since checks and letters are of a special height which will not be changed, so that the character of the machine must be suited to this work. In other words, the 55 height of the feeding wheels cannot be much more than half the height of the average mail matter or bank note. These various conditions, which must be practically complied with, have made it a matter of great 60 difficulty to drive the machine by power. Obviously it is not possible, for example, to make use of horizontal pulleys and driving belts above the surface of the table since these would interfere with the feed of the 65 mail matter.

By the present invention a power drive is proposed which it has been found in practice completely satisfies all requirements.

The invention consists in the improved 70 power drive for canceling machines as hereinafter set forth and claimed.

In the drawings:—Figure 1 is a sectional view of a power drive for a canceling machine embodying the principles of this invention. Fig. 2 is a horizontal section. Fig. 75 3 is a detail end view.

Constructions embodying the invention will of course include the usual large feed rubber 1, and the usual small feed rubber 2, 80 as these feeding wheels are termed in the art, and which are rapidly rotating friction disks on vertical axes slightly elevated above the surface of the canceling table. The small feed rubber has an upwardly extending hub 3, which is smoothly polished, and whose purpose is to furnish a sort of a support for the upper portions of a group of letters or the like being pressed over toward this roll by the right hand. Both of these 85 rollers are positively driven and are intergeared by gears 5 below the table which are immersed in the oil pan under the table which is shown, for example, in my prior patent above referred to. The usual hand drive is likewise illustrated in this prior 90 patent, and these features are not changed by the present invention and are therefore 95 not shown.

As a means of power operation however, 100

the small feed rubber 2 is positively driven by a connection above the table and below the frictional periphery of the roll, and which further is sufficiently compact so as 5 not to interfere with the feed of the matter to be canceled, this latter consideration of course being of equal importance with the first. The power drive satisfying these conditions includes a worm 6 of small diameter 10 on a spindle 7 which runs across the surface of the table away from the location of the matter to be canceled, and which is guided in bearings 8 so as to mesh with a worm gear 9 on the shaft 10 carrying the 15 small feed rubber 2. The horizontally extending spindle will of course rotate at a high rate of speed, and is only well adapted to be driven at such a speed by a direct drive or through a belt from a high speed power 20 source. As is known a belt driven by an electric motor is capable of transmitting rotation at a very high speed, without the objectional wear and noise that would be present with gears or the like. By having 25 this spindle rotate at very high speed, the small feed rubber 2 can also be rotated at fairly high speed notwithstanding a reduction of speed from the worm to gear drive. Furthermore the use of the worm in this 30 way permits the use of a power means which is completely beneath the level of the small feed rubber 2 and scarcely takes up any more vertical height than the thickness of the worm gear itself. On the other hand 35 this mechanism does not project either into or under the table where it would interfere with the oil pan, or beyond the small feed rubber into the path of the matter to be canceled. In other words, the worm gear 40 and the worm are substantially covered by the feed rubber, not projecting beyond the periphery of the same into the path of the mail matter, nor to either side to such an extent as to be an obstruction to the free 45 movement of the hand of the operator. The mechanism furthermore does not project laterally so as to interfere with the large feed rubber. Thus all the conditions mentioned in the preliminary part of the specification 50 are obtained, and a power drive is provided which can be used whenever desired *i. e.* whenever a power source is available.

When the hand power drive for the machine is used, the worm drive must of course 55 be disconnected for obvious reasons, and for this reason the best practical construction embodies a tube or sleeve 12, carrying the two bearings or journals 8 for the worm spindle. This tube or sleeve is received 60 in a split yoke or frame 13 having a screw 14, by which the same can be tightened on the tube or sleeve to hold the same in any position. When the canceling machine is worked by hand the set screw 14 is loosened

and the tube or sleeve 12 pulled out so as 65 to withdraw the worm from the worm gear, after which the machine is entirely free to operate without being hampered at all by the power connection.

The worm, the worm spindle and the 70 worm gear, are all cased in a suitable housing 15 secured to the surface of the table which permits the parts to be lubricated, without exposing the matter to be canceled to lubricant on the one hand, and protecting 75 the parts from grit and dust from the canceled matter on the other hand. The housing is compactly built around the worm gear and the worm, so that the entire housing is substantially located beneath the feed 80 rubber, except for the worm shaft extension in one direction. Thus the device neither interferes with the movement of the articles to be canceled, nor the hands of the operator.

What is claimed is:—

1. In a canceling machine, a vertically extending shaft, a feed rubber fixed to said shaft, a horizontal table on which the matter to be canceled stands when pressed against the feed rubber, a worm gear for the feed rubber below the feed rubber and substantially covered thereby and above the table, and a spindle having a worm extending along the upper surface of the table and meshing with said worm gear, said spindle 90 extending from one side of said worm and said worm being out of the path of the matter to be canceled.

2. In a canceling machine, a vertically extending shaft, a feed rubber fixed to said shaft, a horizontal table on which the matter to be canceled stands when pressed against the feed rubber, a worm gear for the feed rubber below the feed rubber and above the table, a worm meshing with said worm gear, a spindle extending from the side of the worm along the upper surface of the table, and a housing substantially located beneath the feed rubber and covering the worm spindle the worm and the worm gear 95 to prevent the lubricant thereon from reaching the mail matter and the dust from the mail matter from reaching the said parts.

3. In a canceling machine, a feed rubber, a table on which the matter to be canceled 115 stands when pressed against the feed rubber, a worm gear for the feed rubber below the feed rubber and above the table, a spindle having a worm extending along the upper surface of the table and meshing with said worm gear, and means for adjustably locating said worm spindle in different longitudinal positions whereby the drive can be disconnected.

4. In a canceling machine, a feed rubber, 125 a table on which the matter to be canceled stands when pressed against the feed rubber, a worm gear for the feed rubber below the

feed rubber and above the table, a spindle having a worm extending along the upper surface of the table and meshing with said worm gear, a tube or sleeve in which said 5 spindle is journaled, and a yoke therefor for fixing said tube or sleeve in different longitudinal positions.

Signed at New York in the county of New York and State of New York this 21st day of October, A. D. 1912.
